UNITED STATES PATENT OFFICE.

EMIL ZIMMERMAN, OF BUTTERNUT, WISCONSIN.

STOVEPIPE SPARK-ARRESTER.

1,245,303.

Specification of Letters Patent.

Patented Nov. 6, 1917.

Application filed November 8, 1916. Serial No. 130,189.

To all whom it may concern:

Be it known that I, EMIL ZIMMERMAN, a citizen of the United States, residing at Butternut, in the county of Ashland and State 5 of Wisconsin, have invented certain new and useful Improvements in Stovepipe Spark Arresters, of which the following is a specification.

This invention relates to stove pipe spark 10 arresters and the primary object of the invention is to provide a spark arrester adapted to be pivotally mounted in the exhaust pipe of a stove or furnace for obstructing and retarding the flying sparks 15 and cinders so that they will be prevented from escaping through the pipe while at the same time, the device will permit the smoke and gases to freely pass through the pipe.

A further object of this invention is the 20 provision of a stove pipe spark arrester which consists of comparatively few parts and is simple in construction, but durable and well adapted to withstand the rough usage to which devices of this character are 25 ordinarily subjected.

For a full description of the invention and the advantages and merits thereof, reference is to be had to the following description and the accompanying drawings, wherein is 30 illustrated the preferred form of my invention, in which;

Figure 1 is a horizontal transverse section through the stove pipe showing the invention applied thereto.

35 Fig. 2 is a section on the line 2—2 of Fig. 1.

In stoves and heaters which are adapted to consume wood, waste, and other similar quick burning material, it has been found 40 that the sparks and cinders will pass up the flue or stove pipe in an ignited condition and often are the cause of conflagration in adjacent property. In order that the smoke and gases from the burning fuel may be 45 permitted to easily escape and to obtain the proper draft in the stove and to retard the flying sparks and cinders, I have provided the device herein illustrated adapted to be mounted in the flue or stove pipe designated 50 by the numeral 1.

A rotatable damper-rod 2 is mounted for rotary movement in apertures 3 provided at opposite points in the flue 1. One end of the rod is provided with a handle 4 by which 55 the device may be turned for placing the

same into operative or inoperative position within the flue.

A circular ring 5 is mounted upon the rod 2 and is fastened to the rod so that the ring is disposed in the flue when in operative position as clearly shown by Fig. 1 of the drawing. Two series of arcuate rods or wires are provided and have their terminals fastened to the ring 5. These rods are arranged so that one series 6 will be disposed below the other series 7. In other words, the rods in the upper series 7 are provided with an arc of a greater depth than the rods in the lowermost series 6. The lower series 6 includes the rods 8 and the upper series includes the rods 9 and, by referring to Fig. 1 of the drawing, it will be observed that each alternate rod 8 or 9 is included in one or the other of the series 6 and 7 respectively so that the space between two of the rods 8 in the lowermost series is obstructed by one of the rods 9 in the uppermost series although the latter is disposed in a higher plane than the rods 8. Thus, two series of rods are provided for the obstruction of the flying sparks and cinders as they pass upwardly from the fire box of the stove.

This construction permits the smoke and gases to pass freely up the flue, while the 85 burning sparks and cinders are caused to drop back into the fire box of the stove until they are entirely consumed.

Two arcuate supporting rods 10 and 11 are provided, one for each series and these 90 rods extend across the ring 5 in a direction opposite to that of the rods 8 and 9. Warping and distortion of the rods in each series is thereby prevented.

From the foregoing it will be observed 95 that a very simple and durable stove pipe spark arrester has been provided, the details of which embody the preferred form. I desire it to be understood however, that slight changes in the minor details of construction 100 may be made without departing from the spirit of the invention or the scope of the claims hereunto appended.

I claim:

1. A spark arrester comprising a rotatable rod, and a plurality of arcuate rods carried by the said rotatable rod and arranged to comprise two series of rods one disposed above the other.

2. A spark arrester comprising a rotata- 110

ble rod, a circular ring carried by the rod and adapted to be rotated therewith, and a plurality of arcuate rods carried by the ring, each alternate rod being of a greater arc than the adjacent rod.

3. A spark arrester comprising a rotatable rod, a circular ring carried by the rod and adapted to be rotated therewith, two series of arcuate rods having their terminals fastened to the ring, and a supporting rod for each series of rods.

4. A spark arrester comprising a rotatable rod having a handle formed at one end thereof, a ring supported by the rod and adapted to be rotated thereby, a series of rods of arcuate formation having their terminals fixed to the said ring, and a second series of rods of arcuate formation having their terminals fixed to the said ring, the arc of the second series of rods being greater than the arc of the said first series, and a supporting rod for each series of rods.

5. A spark arrester comprising a rotatable rod having a handle formed at one end thereof, a ring supported by the rod and adapted to be rotated thereby, a series of rods of arcuate formation having their terminals fixed to the said ring, and a second series of rods of arcuate formation having their terminals fixed to the said ring, the arc of the second series of rods being greater than the arc of the said first series, the rods of each series extending across the ring in equally spaced relation to each other, the rods in the said second series being disposed above the center of the space between the rods in the lower series, and a supporting rod for each series of rods.

In testimony whereof I affix my signature in presence of two witnesses.

EMIL ZIMMERMAN.
